FLAT HAIR CURLER

Harry Natkiel, Bronx, N. Y., assignor to Henry Engelke, New York, N. Y.

Application October 6, 1936, Serial No. 104,230

2 Claims. (Cl. 132—41)

The purpose of this invention is to provide an improvement in hair curlers of the type upon which the hair is rolled to reduce the weight and also to facilitate placing Bobby pins or the like on the curl.

The invention is a flat strip of material having a substantially continuous longitudinal slot with a flexible member permanently held at one end and with the other end adapted to be snapped on the opposite end of the curler.

It will be appreciated that many types of curlers have been provided upon which the hair may be rolled and which may either remain in the curl or which may be removed after Bobby pins or the like have been placed on the curl to hold the curl; however, curlers of this type have formerly been made of a tubular shape or round and with the hair wrapped therearound it is difficult to slip a hair pin over the hair. The size and weight of these devices are also objectionable.

The object of the invention is therefore to provide a device for replacing hair curlers of this type which may be made of a flat piece of material and which will serve the same purpose.

Another object is to provide a hair curler of this type which is of such a light weight that it is not objectionable if permitted to remain in the hair.

Another object is to provide a curler of this type which has an elastic member adapted to hold the hair thereon.

And a further object is to provide a curler of this type having an elastic member for holding the hair in which the elastic member extends through the device and is arranged so that it may be clipped on either side so that it may be used by either a right or left handed person.

And a still further object is to provide an improved hair curler of this type which is of a simple and economical construction.

With these ends in view the invention embodies a flat piece of relatively thin material having a longitudinal slot extending substantially through the flat piece of material with the sides at the outer end of the slot beveled outward and with an elastic or flexible member secured to the flat piece of material at a point adjacent the closed end of the slot which is provided with a clip on the outer end which is adapted to snap over the open end of the device.

Other features and advantages of the invention will appear from the following description taken in connection with the drawing, wherein:

Figure 1 is a view showing the device as it would appear in use.

Figure 2 is a view showing the device as a portion of the hair is about to be rolled thereon.

Figure 3 is a plan view of the device with the elastic member in the free position.

Figure 4 is a side elevation of the device as shown in Figure 3.

Figure 5 is a view similar to that shown in Figure 3 showing the end of the elastic member snapped over the end of the device.

Figure 6 is a view showing an alternate design in which the elastic member is placed through an opening in the device and then the free end placed in a slot in which it is gripped and held.

Figure 7 is a detail showing the method of holding the elastic member in the device shown in Figure 6.

Figure 8 is a similar detail showing the elastic member with a clip on each end so that either end thereof may be snapped over the opposite end of the device.

Figure 9 is a detail showing a clip of the alternate design which is adapted to snap in between the beveled surfaces at the end of the device.

Figure 10 is a side view of the clip shown in Figure 9.

Figure 11 is a view showing an alternate design in which a flat strip, preferably made of metal, is hinged to one end of the device.

Figure 12 is a plan view of the design shown in Figure 11.

Figure 13 is a cross section through the device shown in Figure 3.

In the drawing the device is shown as it may be made wherein numeral 1 indicates the flat strip of material, numeral 2 the elastic, and numeral 3 the holding clip on the end of the elastic.

The member 1 is preferably made as shown in Figure 3 of a flat strip of material about $\frac{3}{64}$ of an inch thick, however the thickness is immaterial and this is provided in about the size shown in Figure 3. The device in this design is provided with a substantially continuous slot 4 which extends from a point 5 adjacent the inner end to a point 6 and the sides thereof are then beveled outward forming surfaces 7 and 8 which guide the hair into the slot 4.

The opposite end of the device is provided with a relatively narrow clamp 9 which is preferably rolled as shown in Figure 4 and crimped downward upon the end of the elastic 2 to permanently hold the elastic in place at this end of the device. The clip 3 is arranged on the opposite end of the device and this is

- preferably formed of a tubular shaped piece of material with notches 10 and 11 therein and the central part 12 is also crimped inward permanently securing the clip on the end of the elastic.
- 5 Sections 13 and 14 at the ends of the clip are formed with slots 15 on the inner side of the clip and these slots are arranged so that as the clip is snapped over the end of the device the ends of the parts forming the two sides snap into 10 the slots 15 so that the clip is secured on the end of the device as shown by the dotted lines in Figure 4.

The hair is first drawn outward and the ends are placed in the slot 4 as shown in Figure 2 15 with the elastic open and the device is then rolled forming a roll of hair thereon and when this is tight against the head the clip 3 may be snapped on the end thereof and it will be noted that with the device rolled upon the hair forming 20 a curl it may stop against the head with either side outward so that it is desirable to snap the elastic on either side as it is desired to hold the curl as close to the head as possible. For this reason the elastic may be provided with clips 3 25 at each end as shown in Figure 8 and this may be placed through a hole 16 in the device as shown in Figure 6 so that one end will prevent the elastic passing through the hole as the other is clipped over the opposite end of the device. It will be 30 understood that the elastic of either design may be provided with a clip at each end and the hole 16 may also be used in the device shown in Figure 3 instead of the gripping member 9.

The elastic may also be held by placing the 35 end through the hole 16 shown in Figure 6 and then wedging the end in a slot 17 in the end of the device which in the design shown in Figure 6 is indicated by the numeral 18 and this end of the elastic will then be held in the position shown 40 in Figure 7.

It will also be understood that the clip on the end of the elastic may be made as shown in Figures 9 and 10 in which the clip is indicated by the numeral 19 and this is formed of a triangular 45 shape, with the sides 20 and 21 corresponding with the sides 7 and 8 and these sides are provided with slots 22 and 23 into which the edges 7 and 8 pass. It will be understood however that this clip may be of any other type or design and 50 may be arranged in any manner.

In the design shown in Figures 11 and 12 the elastic is replaced by a flat relatively thin metal strip 24 which is hinged to the device which is indicated by the numeral 25 at the point 26 and the opposite end is provided with a clip 27 that 55 may be snapped into the space between the surfaces 7 and 8. The member 24 may be provided with an upwardly curved portion as shown at the point 28 in order to insure continuous contact 60 thereof with the surface of the member 25.

It will be understood therefore that this device may be formed with a base member consisting of a flat piece of material with a slot extending continuously through the central part thereof and any elastic or flexible means may be 5 provided which may be fastened at each end for holding the hair thereon.

It will be understood that other changes may be made in the construction without departing from the spirit of the invention. One of which 10 changes may be in the exact design or shape of this flat metal strip, another may be in the use of other means for holding the elastic thereto, and still another may be in the use of other means for removably holding the end of the 15 elastic to the open end of the device in place of the clip 3.

The construction will be readily understood from the foregoing description. In use the device may be provided as shown and described and it 20 will be noted that it may be started upon a portion of the hair as shown in Figure 2 and then rolled to the position shown in Figure 1 where the flexible member may then be snapped into place so that the device will be held in this position, 25 and one of these devices may be placed on each curl or hair pins similar to the pin known as the Bobby pin may then be placed over the curl and it will be noted that with this device made of flat material the pins may readily be placed over the 30 hair, whereas with the hair wrapped tight around a cylinder there is substantially no space between the hair and surface of the device to permit the hair pin being inserted in place. After hair pins have been placed upon one or both 35 ends of the curl the device may then be removed if desired.

Having thus fully described the invention what I claim as new and desire to secure by Letters Patent, is:—

1. A hair curler comprising a flat strip of sheet material, having a slot extending inward from one end substantially to the opposite end, forming two legs of flat material positioned in the same plane and lying edge to edge, and joined together at one end forming the head of said curler, said head having recesses in the opposite sides beyond the end of the slot, and an opening therethrough also beyond the end of the slot, and the opposite end of said curler, into which 50 the said slot extends, shaped with outwardly sloping surfaces forming the inner edges of the ends of said legs.

2. A curler as described in claim 1, characterized by an elastic strand mounted in the head 55 thereof, and having an enlarged bead at the opposite end adapted to be inserted and held between the sloping surfaces of the ends of said legs.

HARRY NATKIEL. 60
